UNITED STATES PATENT OFFICE.

EMIL JUST, OF BRONX, NEW YORK.

INTERNAL-COMBUSTION ENGINE.

Application filed April 26, 1927. Serial No. 186,607.

This invention relates to engines and particularly to power generators of the internal combustion type.

Such motors, especially as are used in automobiles, are generally composed of four or more cylinders and are rather bulky and cumbersome.

Furthermore, they are complicated and expensive, both initially and the cost of upkeep, containing a great amount of parts entirely out of proportion to the resulting work.

It is therefore the main object of this invention to provide an internal combustion engine that is relatively small and compact, comprised of only one combustion chamber in which two pistons are operable.

A further object is in the provision of an inexpensive engine having few and simple parts and which is capable of developing a greater power, in proportion to the size and cost of the device, than the engines used heretofore.

These and other objects, which will become apparent as the description progresses, are accomplished by the novel construction, combination and arrangement of parts, herein-after described and illustrated in the accompanying drawing, forming a material portion of this disclosure, and in which:—

30 Figure 1 is a vertical sectional view taken approximately through the center of the device.

Figure 2 is a partial side elevational, partial sectional view taken on line 2—2 of Figure 1.

35 In the drawing, the numeral 5 generally designates a combustion chamber having its lower side walls flared outwardly at 6, its upper wall 7 curving downwardly at its center.

40 Extending outwardly from the side walls are cylindrical heads 8 provided with spark plugs 9 connected to a source of electrical energy and inlets 10 connected to a source of fuel, such as gasoline.

45 Disposed below the heads 8 are outlets 11 constituting exhaust ports for the burnt gases, as will later be seen.

50 Fixed transversely in the chamber 5, just above the flared portion 6, are a pair of pivot bolts 12 on which are rotatably mounted flat lever arms 13—13', closely fitting the adjacent walls and extending from the top of the chamber 5 almost to the bottom thereof.

55 Fixed on the arms 13—13' to fit the open-

ings of the heads 8, are raised conical discs or piston heads 14, the backs of the arms being connected by a pivoted link 15.

Pivoted to the lower end of the arms 13—13' are levers 16—16' having slots 17—17' 60 engaging pins 18—18' fixed in cranks 19—19' fast on shafts 20—20' journaled in bearings 21 and extending beyond the chamber 5.

The pins 18—18' are connected by a link 22 so that both shafts 20—20' will operate simultaneously.

Thus, in operation, as shown in Figure 1, the lever arm 13 is positioned so that its disc 14 projects into the adjacent head 8 to compress the gas which has been entered therein 70 through the inlet 10.

When the spark is applied, the gas will explode and the lever arm 13 will be forced toward the center of the chamber, which action through the crank system described, rotates the shafts 20—20'.

By this time the arm 13' has been moved to compress the gas in the opposite chamber 8 where the action will be repeated to give the shafts 20—20' a continuous motion.

It will thus be noted that because of the length of the arms 13—13', the power imparted to the shafts 20—20' will be much greater than has been in engines of this type heretofore.

It will further be noticed that because of the size and simplicity of the motor, the cost, both initially and the upkeep will be materially less than before.

Although the foregoing is descriptive of the preferred embodiment of my device, changes may be made without departing from the scope of the appended claim.

Having thus described my invention, what I claim as new and desire to secure by Letters Patent, is:—

An internal combustion engine comprising the combination with a chamber having means to produce a spark and inlet and outlet ports, of a pair of flat, rectangular levers pivotally mounted in said chamber, raised, conical piston heads on the ends of said levers, said levers being adapted to be oscillated by successive explosions in said chamber, a pair of shafts, and a crank lever system whereby power is transmitted from said levers to said shafts.

In witness whereof I have affixed my signature.

EMIL JUST.
